CHARGE FORMER FOR CIGAR MACHINES

Henry H. Wheeler, Brooklyn, N. Y., assignor to
International Cigar Machinery Company, a
corporation of New Jersey

Application June 3, 1939, Serial No. 277,160

18 Claims. (Cl. 131—21)

This invention relates to charge formers for cigar machine filler feeds, its main object being to provide a novel apparatus and method for bunch charge forming, the particular apparatus selected to exemplify the invention constituting an improvement of the device disclosed in Patent No. 1,791,558, issued February 10, 1931, to V. G. Hanson.

In the device referred to, the filler tobacco is fed in a layer of the proper width equal to the length of the bunch to be made, by an intermittently driven belt against the fingers of a weight-tensioned charge-retaining plate which blocks the advancing tobacco layer until the density of the accumulated mass is sufficient to permit the exerted pressure to overcome the weight of the retaining plate, whereupon the thus properly condensed filler advances into the charge forming chamber. When advanced to the proper distance for one bunch charge, a trip arrangement is actuated which stops the feed belt and a cam operated knife severs the charge in the forming chamber from the fed layer. As the charge is cut, the measuring fingers are pulled downward by a cam operated rod, permitting a row of reaper fingers to remove the severed charge. The latter is then inserted by a row of pusher fingers into a charge transfer which deposits the same upon the rolling table of the machine whereon a rolling apron actuated by a rolling pin rolls it within a binder to form a cigar bunch.

While in the device shown in the above mentioned Hanson patent the measuring chamber is of rectangular cross-section which necessitates the re-shaping of the charge on the rolling table and thereby places undue stresses on the rolling apron, in the present invention the charge-former parts are so shaped as to provide a measuring chamber of circular cross-section. The stream of tobacco advanced by the feed belt is much thinner than in the former device and is caused to curl into a cylindrical charge of the proper cross-section. When enough tobacco has been fed to completely fill the forming chamber to the desired density, the weight-balanced measuring fingers actuate the trip arrangement, thereby stopping the feed during cutting of the charge, as before.

To insure the proper curling of the charge, in a modified form of the invention, the cylindrical inner surface of the forming chamber may be provided with one or more positively driven curling rollers which propel the advancing feed layer as it enters into the measuring space. This forming chamber may be so constructed, as shown in

the modified embodiment of the invention to also serve as a transfer for the charge to the rolling apron.

In the accompanying drawings which form a part of this invention and in which:

Fig. 1 is a sectional side elevation of the improved charge former;

Fig. 2 is an end elevation of the same, on line 2—2 of Fig. 1; Fig. 3 is a plan view thereof equipped with a cross feed;

Figs. 3—4 and 5 are enlarged sectional side elevations of the improved charge former at different stages of cutting and transferring the bunch charge;

Fig. 6 is a sectional side elevation showing a modification of the improved charge former; and

Fig. 7 is a sectional end elevation on line 7—7 of Fig. 6.

Referring to Figs. 1 and 2, the intermittently driven feed belt 10, which runs over pulleys 11, 12, 13 and 14, advances the bunch-length wide, thin layer of filler tobacco T under the leveling star wheels 15 and guide fingers 16, whence the feed rollers 17 pass it on to the platform 18 and into the measuring chamber. The latter is formed by the arcuate ends of the fingers of the movable charge retaining plate 19 coating with the concave under faces of the stationary guide bars 20 and movable forwardly in slots therein. The retaining plate 19 is attached to an arm 22 swinging on stationary studs 23. The upper end of the arm 21 is connected by a rod 24 with an arm 25 on one end of a fulcrum shaft 26, the other end of said shaft carrying a weight arm 27 which is equipped with removable weights to vary the resistance of the plate to the tobacco fed into the measuring chamber.

As the measuring chamber fills up, the thin tobacco layer T curls up into a cylindrical spiral, as shown in Fig. 3, the under faces of the bars 16 being set somewhat higher than the thickness of the tobacco stream to permit the same to curl up while gradually pushing the plate 19 forward and raising the weight arm 27 in doing so. When the charge T' has been compacted to the proper density, an adjusting screw 29 bearing against a nose on weight arm 27 and carried by arm 30 trips a lever 31, thereby causing the latter to disengage pawl 32 from ratchet 33 and thus stop the feed belt 10, and more fully described in Patent No. 1,791,558, above mentioned.

During the dwell of the feed belt, a cam operated knife 34 cuts the bunch charge T', whereupon a rod 35 pivoted to swinging frame 22 and actuated by a cam lever 36, pulls the retaining

plate 19 downward, as shown in dotted lines in Fig. 3, thus clearing the way for the reaper fingers 37 which have come down from their dotted rest position to their operating position 37' during the cutting process, to push the severed charge T' forward.

Having advanced the charge T' a given distance, Fig. 4, the fingers 37' stop at 37'', move up into the dotted position 37''' and back into rest position 37, from which they again descend into operating position 37' as the next charge is being cut. In this position of the charge the reaper fingers 38 at the forward ends of the reaper finger 37 engage with the bunch charge T', as shown in Fig. 5, and, upon the advance of the fingers after the cutting of the next charge, push the charge T' into the pocket 39 of a charge transfer 40, such as described in U. S. Patent 1,838,192 granted December 29, 1931 to R. E. Rundell. This transfer descends into position 40' while its pocket 39 rotates to a position wherein its plunger 41 ejects the charge into a pocket of the rolling apron 42, this pocket being formed by the descent of the transfer 40. The rolling pin 43, when passing over the rolling table 44, after the return of the transfer 40, will then produce a cigar bunch by rolling the cylindrical charge T' into a binder previously deposited upon the apron 42. During its entire travel from charge-cutting position to pocket 39, the charge T' is firmly held between the platform 18 and the guide bars 20, and the walls of the pocket 39 are made to fit snugly about the charge. The latter, therefore, retains its cylindrical shape, relieving the rolling apron of the extra strain of shaping the bunch.

In the modification shown in Figs. 6 and 7, the guide bars 18, platform 20, reaper fingers 37, 38 and transfer 40 of Figs. 1 to 5 are omitted, the feed belt 10 advancing the filler tobacco layer T into a swingably supported forming chamber 45 which delivers the formed charge directly on to the rolling apron 42.

This forming chamber consists of a partly open cylindrical chamber 45 connected by arms 46 to a hub 47 which is mounted on a shaft 48 swingable in bearings of the bunch machine. The lower portion 49 of chamber 45 is pivoted to the upper portion on pins 50 which form the trunnions of a roller 51 extending between the arms 46. The pivoted part 49 of the forming chamber at each side has a rearward extension 52 which carries a compression spring 53 bearing against one of the arms 46, these springs holding noses 54 of the extension 52 against stop pins 55 carried by the upper portion of forming chamber 45, thus holding the part 49 in its operative position.

When in the receiving position, shown in full lines in Fig. 6, the concave ends of the upper and lower portions of the chamber 45 rest against the stationary rollers 56 and 57 turning in bearing lugs on support blocks 58 and 59, the rear face of the lower block 59 being shaped to form part of the cylindrical receiving surface between the rollers 56 and 57. The rollers 51, 56 and 57 are so mounted as to project a small distance into the forming chamber. The rollers 56 and 57 are driven from the main shaft 60 of the machine by a chain 61 running over a sprocket 62 on a shaft 63 concentric with the receiving position of the forming chamber 45 and carrying a gear 64 meshing with gears 65 and 66 on the trunnions of rollers 56 and 57, respectively. The hub 47, on a screw arm 67, carries a weight 68 adjustably fastened thereon by thumb nuts 69, this weight

taking the place of the balance weight 27, 28 of Fig. 1. To the hub 47 are attached cam pieces 70 on the projecting noses of which rest the side arms 71 of a frame carrying the knife 72, the knife frame being pivoted on a shaft 73 which has a lever 74 connected by the rod 24 to arm 25 on shaft 26 of the feed control. The knife frame is held against the cam pieces 70 by springs 75 attached to the arms 71. The pivot shaft 48 of the forming chamber has a crank arm 76 which is connected by a rod 35 to the cam lever 36.

The stream of filler tobacco T is carried by the feed belt 10 under a compression belt 77 running over rollers 78 and 79, the belt 77 being driven in synchronism with the feed belt by a chain 80 from a sprocket 81 on drive pulley 11 of the feed belt, the chain 80 driving a gear 82 meshing with a gear 83 on the shaft of roller 79. The compressed layer, in entering the forming chamber, is rolled up into a cylindrical charge by the action of the rollers 56, 51 and 57. When the chamber is filled to the proper density, as predetermined by adjusting the balance weight 68, the cam pieces 70 trip the knife frame 71, the latter dropping on to the arcuate portions of the cam pieces 70, thereby, through rod 24, stopping the feed belt 10 and, through springs 75, causing the knife 72 to cut the charge in chamber 45, the blocks 58 and 59 being suitably cut out to permit the passage of the knife. Thereupon the cam lever 36, through rod 35 and arm 76 on shaft 48, swings the chamber 45 into the delivery position 45', shown in dotted lines, the cam-actuated lever 36 being so timed as to allow abundant time for the filling of chamber 45 and for cutting the charge. While in transit the lower portion 49 of the forming chamber engages the rolling apron 42 and forms the rolling pocket 42'. In the delivery position, the extensions 52' of the hinged portion 49' engage with stop pins 84 attached to the frame of the machine, thereby compressing the springs 53' and opening the chamber 45', so that the charge T' is released and deposited on the rolling apron 42'. The latter is then slowly paid out by its take-in roller 85, which is controlled by an endless chain 86 actuated by a cam lever 87, thereby gently lowering the charge T', so that upon the return stroke of lever 36 the path is clear for the upward motion of the forming chamber. The charge, which has retained its cylindrical shape during its descent on the rolling apron, is then rolled into a cigar bunch by the rolling pin 43, as before.

Before the cam lever 36 has completed its down stroke which restores chamber 45 into receiving position, the action of the feed control temporarily raises the knife frame 71 so that, on arriving in receiving position, the cams 70 will pass into trip engagement with the knife frame, ready to stop the feed and to actuate the knife upon the completion of the next charge. When the cam pieces 70 trip the knife frame the rod 24 is urged in the direction of the arrow (Fig. 6) thereby swinging the arm 25 in a direction which causes its nose to press the stop screw downwardly and thereby swing the arm sufficiently to permit the spring-pressed trip lever 31 to disengage the pawl 32 from the ratchet 33. Thus the driving of the drum through the planetary gearing (not shown) is terminated, as described in Patent 1,791,553 referred to above, until reinstated in the manner described in said patent, whereby the trip lever is disengaged from the pawl, the knife frame being raised to inoperative position by mechanism (not shown) and the trip lever 31

being retained in its ineffective position by the arm 30.

It is advantageous to feed a thin stream of filler tobacco to the measuring chamber or charge transfer for curling therein. A suitable construction for this purpose is illustrated in Fig. 8 wherein a cross-feed 100 advances a wide thin stream of filler tobacco from which bunch lengths are severed and transferred sidewise to a filler feed 101 having a construction similar to that shown in Figs. 1-4 hereof. Hence a filler stream having a thickness preferably of one half or less of the desired thickness of bunch charge may be fed into the measuring chamber. The cross feed may have the construction shown in the patent to W. B. Bronander, No. 1,740,571, except that a thin stream of tobacco instead of one of bunch-charge thickness is fed on the cross-feed and the width of the stream thereon is sufficient to supply sufficient filler for a bunch charge in each bunch length severed therefrom, although a cross feed having a construction similar to that disclosed in the Lindblad Patent No. 1,977,994, October 23, 1934, may be employed to form bunch lengths and deliver them to the filler feed 101.

What is claimed is:

1. The combination with a yielding member, of devices for advancing a continuous shallow stream of filler tobacco against said member and curling it upon itself to form a roll of filler tobacco and compact the same to a predetermined density, and means for separating from said stream of tobacco the roll of tobacco so formed and compacted against said yielding member.

2. The combination with a yielding member, of devices for advancing a continuous shallow stream of filler tobacco against said member and curling it upon itself to form a roll of filler tobacco and compact the same to a predetermined density and displace said member a predetermined distance, and means for separating from said stream of tobacco the roll of tobacco so formed and compacted against said yielding member, said yielding member having an arcuate end against which the stream of tobacco is advanced, and said devices including guide bars having concave inner faces coacting with said arcuate end to curl up the stream of tobacco into a roll as it displaces said member.

3. The combination with a yielding member, of devices for advancing a continuous shallow stream of filler tobacco against said member and curling it upon itself to form a roll of filler tobacco and compact the same to a predetermined density, and means for separating from said stream of tobacco the roll of tobacco so formed and compacted against said yielding member, said member being provided with a semi-cylindrical pocket, and said devices including driven rolls coacting to feed the stream of tobacco into said pocket and curl the same into a roll therein and engaging said roll of tobacco.

4. The combination with a yielding member, of devices for advancing a continuous shallow stream of filler tobacco against said member and curling it upon itself to form a roll of filler tobacco and compact the same to a predetermined density and displace said member a predetermined distance, means for separating from said stream of tobacco the roll of tobacco so formed and compacted against said yielding member, and means for incapacitating said devices when said member has been displaced through said predetermined distance.

5. The combination with a yielding member, of

devices for advancing a continuous shallow stream of filler tobacco against said member and curling it upon itself to form a roll of filler tobacco and compact the same to a predetermined density, and means for separating from said stream of tobacco the roll of tobacco so formed and compacted against said yielding member, a charge transfer adapted to receive the severed charge roll of tobacco and firmly hold the same, carry it to binder-applying position, and reapers for inserting the severed charge into said transfer.

6. The combination with a yielding member, of devices for advancing a continuous shallow stream of filler tobacco against said member and curling it upon itself to form a roll of filler tobacco and compact the same to a predetermined density, and means for separating from said stream of tobacco the roll of tobacco so formed and compacted against said yielding member, said member being provided with a pocket adapted to receive the charge of tobacco, and mechanism for moving said member into a position wherein the charge is deposited to be rolled within a binder.

7. The combination with mechanism for forwarding a layer of filler tobacco approximately equal in width to the length of a cigar bunch, of a severing device, a yieldably mounted measuring device spaced beyond said severing device in the direction of movement of said layer, means coacting with said measuring device to halt the operation of the forwarding means when said device is displaced a predetermined distance from said severing device by said layer, and means for curling said layer on itself prior to severing.

8. In a cigar bunch making machine, the combination with means for forwarding a layer of tobacco containing substantially more than sufficient tobacco for a single bunch charge, of means for curling the forward portion of said layer to form a generally cylindrical bunch charge, and mechanism for severing the curled portion from the remainder of the layer to separate the charge.

9. The combination with a filler transfer adapted to admit a stream of filler tobacco and curl the same upon itself to form a roll of filler tobacco, means for feeding a continuous stream of tobacco into said transfer, a device for separating the roll so formed in the filler transfer from said stream of tobacco, said transfer being constructed to constrict said roll, and mechanism for moving said transfer to deposit said roll in binder-applying position.

10. The combination with a measuring chamber, of means for feeding a stream of tobacco into said chamber, and a member having a curved portion extending into said chamber into position to oppose said stream of tobacco and cause it to curl upon itself to form a roll.

11. The combination with a measuring chamber, of means for feeding a stream of tobacco into said chamber, a member having a curved portion extending into said chamber into position to oppose said stream of tobacco and cause it to curl upon itself to form a roll, mechanism for withdrawing said member from the measuring chamber following the formation of said roll, and devices for severing said roll from said stream and removing it from said chamber.

12. The combination with means for feeding a continuous stream of tobacco, of a measuring chamber adapted to admit said stream of tobacco and cause it to curl upon itself to form a roll

of tobacco, said chamber being provided with concave surfaces acting to curl the stream of tobacco into cylindrical form.

13. The combination with means for feeding a continuous stream of tobacco, of a measuring chamber adapted to admit said stream of tobacco and cause it to curl upon itself to form a roll of tobacco, said chamber being provided with driven rollers coacting to engage and curl the stream of tobacco within said chamber and said means comprising a set of opposed members arranged to engage said stream at a position anterior to said chamber and coacting to forward the stream into said chamber and into engagement with said rollers.

14. The combination with a yieldingly mounted measuring chamber adapted to admit an advancing stream of tobacco and be bodily displaced thereby, of mechanism for feeding a continuous layer of tobacco into said chamber and adapted to be incapacitated by said chamber when the latter has been displaced a predetermined distance by the pressure of said layer.

15. The method comprising advancing a stream of tobacco, curling the forward end of the stream upon itself to form a roll of tobacco, and separating the roll so formed from said stream.

16. The method of forming bunch charges and delivering them to a bunch rolling apron which comprises advancing a stream of tobacco, curling the forward end of the stream upon itself to form a roll of tobacco, separating the roll so formed from the stream, and simultaneously holding said roll against uncurling and transferring the same to the bunch rolling apron.

17. In a cigar machine, the combination with 10 a member having a pocket adapted to admit a layer of tobacco and engage the forward end of said layer and thereby curl said end upon said layer, of means disposed at a position anterior to said pocket to engage a layer of tobacco at a 15 region anterior to said pocket and operating to feed the layer of tobacco into said pocket whereby said layer will be coiled upon itself within the pocket.

18. In a cigar machine, the combination with 20 a binder applying mechanism, of means for forming a bunch charge of long filler tobacco rolled upon itself, and a member adapted to engage the exterior of the rolled bunch charge to constrict the same, and transfer it to said mechanism for application of a binder thereto.

HENRY H. WHEELER.
